CURTAIN THREADING HELPER

Pennie M. Moss, Humboldt, Tenn.

Application May 7, 1954, Serial No. 428,333

1 Claim. (Cl. 223—105)

The invention relates to devices for facilitating the guiding or threading of curtain rods through the hem of a curtain or drape.

The problem of guiding curtain rods through the hem of a curtain is well recognized. The rods that are employed to hang curtains and drapes generally have blunt ends with sharp corners. It is therefore an arduous and difficult operation to guide the rod along its proper path. Furthermore, curtains are often made of delicate material that is susceptible to tearing. Hence, the sharp corners on the end of the conventional curtain rod are apt to tear holes in the curtain unless great care is exercised in threading the rod through the hem. This then is a time-consuming job that requires patience and much effort.

It is therefore a primary object of this invention to provide a device that will facilitate the operation of guiding a curtain or drape rod through the hem of a curtain or drape.

A further object of this invention is to provide a curtain threading attachment that is adapted to fit on the end of a curtain rod.

A further object of this invention is to provide a curtain threading device that will prevent any possibility of tearing the curtain when threading a rod therethrough.

A further object of this invention is to provide a curtain threading device that will permit the threading operation of a curtain rod to be quick and easy to perform.

A further object of this invention is to provide a curtain threading device that is of simple construction, easy to manufacture and adaptable for convenient attachment to the end of a curtain rod.

These and other objects of the present invention will become apparent from the following description considered with the drawings in which—

Figure 1 is a side view of the invention.

Figure 2 is a perspective view of the invention shown 50 inserted in a curtain rod ready for use, and

Figure 3 shows the invention in operative use.

In accordance with the above objects, the present invention comprises a device that is conveniently inserted into the end of a conventional curtain rod. A ring-like 55

2

construction on one end of the attachment thereby extends beyond the rod to present a smooth curved surface to the curtain. Being curved, the curtain offers little resistance to the rod as it is pushed through the hem, and there is 5 no possibility of damage to the curtain. The rod is thereby quickly and efficiently guided along its proper path.

Referring now to the drawings, the attachment is generally indicated by numeral 10 and comprises a ring 11 having two extending arms 12 and 13. The arms are preferably made integral with the ring and of flexible material. Both the ring and arms may be made of a heavy gauge wire. Since the arms 12 and 13 are secured to the ring at one end and unsecured at the other end, they are flexible and free to move together under pressure. The outer ends 14 and 15 of the arms are rounded to allow for easy insertion into a rod.

In Figure 2 there is shown the attachment 10 inserted in the end of a rod 16. It is seen that the arms 12 and 13 are slightly pressed together by the inner surfaces of the rod to provide a friction engagement. This is to prevent the attachment from slipping out of the rod during use thereof. Also, the ring 11 is of slightly greater diameter than the width of the rod, so that it will not slide into the rod as the curtain 17 is being threaded.

With the attachment properly inserted in the rod 16, the curtain is conveniently pushed over the rod in the direction of arrow 18, as seen in Figure 3.

Though the present invention has been described with reference to a specific embodiment thereof, it is understood that this is not to be considered as limiting the scope of the invention, as defined in the appended claim.

Having described the invention, what is considered new and novel is:

35 A device for gripping a curtain rod through the hem of a curtain comprising a ring of round wire of a diameter larger than the width of a curtain rod, a pair of curved flexible wire arms integrally projecting from said ring, and coplanar with the latter, said pair of curved flexible wire arms being spaced apart less than the outer diameter of said ring at their joining ends with the latter, and said arms being spread apart intermediate their ends to assume a distance from each other greater than the diameter of said ring, said arms being adapted to be received 40 in the end of a curtain rod with a friction fit, and a rounded end on each of said arms to facilitate the insertion of said arms in the end of a curtain rod.
